TENTERING MACHINE

Richard E. Rusden, Providence, R. I., assignor to
The Textile-Finishing Machinery Company, a
corporation of Rhode Island

Application July 29, 1932, Serial No. 625,822

17 Claims. (Cl. 26—57)

This invention relates to a tentering machine, and has for one of its objects to provide a machine in which the driving mechanism for the chain on the rails will be better supported than the driving mechanism which has heretofore been used in tentering machines.

Another object of this invention is the provision of a construction in which the weight of the driving parts will be supported independently of the drive shaft that a more even drive may be had and a more easy sliding adjustment of the parts may be had than where the weight of the parts are somewhat supported upon the driving shaft on which they are to slide.

Another object of this invention is the provision of a balanced mechanism for the adjustment of the chain rails by which no binding action on the drive shaft may be had during adjustment of the rails toward or from each other to vary the size of the machine for different widths of cloth.

Another object of the invention is the provision of a construction by which a lubricant retaining flange is provided about the end of the rail whereby the machine may be maintained in cleaner and better lubricated condition than where the grease is allowed to escape from the end of the rail where the chain extends about the sprocket gear.

Another object of the invention is the provision of a construction of chain rail which may be detached for taking the drive mechanism apart and for purposes of machining the parts.

A further object of this invention is the provision of a construction of sprocket gear which may be formed at less expense than heretofore.

A still further object of the invention is the provision of a sprocket which may be formed in two parts with the chain engaging part formed of silent or non-metallic material for the more quiet running of the machine.

With these and other objects in view, the invention consists of certain novel features of construction, as will be more fully described, and particularly pointed out in the appended claims.

In the accompanying drawings:—

Fig. 1 is a side elevation of the tentering machine with the length thereof foreshortened as indicated in broken lines.

Fig. 2 is a top plan view thereof.

Fig. 3 is a sectional view through the bridge rails and showing in elevation the driving gear housing and a portion of the chain rail in section and attached to the top thereof.

Fig. 4 is a central sectional view through the driving gear housing.

Fig. 5 is a plan view of one of the ends of the chain rail showing the driving mechanism for adjustment of the rail toward and from the center of the machine.

Fig. 6 is a top plan view of the end portion of the chain rail.

Fig. 7 is an end view of the parts shown in Fig. 6.

Fig. 8 is a sectional view on substantially line 8—8 of Fig. 6.

In the usual tentering machine the chain rails are slidably supported upon suitable standards so that they may be moved toward and from each other by oppositely threaded shafts at the ends of these rails. The driving mechanism for the chains on the rails is usually supported from each of the rails at the head end of the machine with a drive shaft extending through the gear housings for driving the gearing therein. The housings move with the rails and slide along the drive shaft as the rails are adjusted. This arrangement frequently causes some of the weight of the casing and gears to be exerted upon the drive shaft and thus sliding adjustment along this shaft is difficult. Further, the single threaded shaft for adjustment is usually placed at one side of this drive shaft and if there is any looseness between the parts there is a tendency for the threaded shaft to tend to twist the parts about the drive shaft and cause the parts to bind thereon. Also, it is found that in machines of this character that, in order to take apart and remove or replace any of the driving gears it is necessary to remove the drive shaft and drop the gearing out through the bottom of the casing.

In order to avoid these undesirable results, I have supported the driving mechanism upon two bridge rails and upon this driving mechanism the chain rail rests so that no weight of the driving mechanism is carried by the chain rail and no weight will rest upon the drive shaft which is located between the bridge rails and extends through the gear mechanism. I have also provided two screw shafts for adjustment, one located on each side of the drive shaft and in substantially the plane thereof so that no binding action can occur along the drive shaft as adjustment is had; and I have also provided on the chain rail a construction by which a flange extends entirely around the curved end of the rail so that no grease or other lubricant is discharged over this end of the rail as the machine

is in operation, the parts of which are readily detachable so that they may be easily taken apart for interchange or replacement of the driving parts when such manipulation is desired. Also, 5 I have provided a construction of sprocket, the teeth of which may be readily interchanged and one in which fiber or non-metallic material may be used for more silent running; and the following is a detailed description of the present 10 embodiment of this invention illustrating the preferred means by which these advantageous results may be accomplished.

With reference to the drawings, the machine 15 consists of the support standards 10 with cross bars 11 extending between the standards on opposite sides of the machine and on which the chain rails, designated generally 12, are supported for sliding movement.

At the head end of the machine, where the 20 driving of the tenter chain occurs, there is provided a pair of bridge rails 13 which are of generally channel shape construction as illustrated in Fig. 3 and are connected at spaced intervals by the rods 65 threaded at their end portions 25 and provided with securing nuts 66. These rails support a casing or gear housing 14 by reason of the shoulders 15 on the top and 16 on the bottom on opposite sides of the housing engaging the upper and lower machined surfaces 17 and 18 30 of the bridge rails, this casing being freely slideable laterally of the machine toward and from the center of the machine along these rails and supported thereby. Through the lower portion of this casing 14 there extends a drive shaft 19 35 supported in fixed bearings at its ends and which is driven from a suitable source of power in the usual manner of manipulation of machines of this character. It will be of course understood that there are two chain rails for engaging the 40 opposite edges of the web of fabric and the parts now being described are in duplicate, one being secured to each rail.

Within the casing 14 which consists of a body 45 part supported by the rails, a top cover 14a and bottom cover 14b suitably secured together by bolts as shown in Fig. 4, there is mounted a spiral bevelled gear 20 attached to a hub portion 21 which is keyed to the shaft 19 as at 22. The hub 50 is rotatably supported in ball bearings 23 mounted in the casing, whereby rotation of the shaft 19 transmits rotary movement to the gear 20.

A spiral bevelled gear 24 meshes with the gear 20 and is secured to a hub 25 fixed to the portion 26 of the stub shaft 27 mounted to rotate in the 55 ball bearing 28 suitably supported in the upper portion of the casing. This shaft is driven by the intermeshing gears 20 and 24.

A collar member 29 forming a casing and support extends upwardly from the casing 14 and 60 surrounds the stub shaft 27. The rail 12 of the machine is supported upon this collar portion while the ball bearing 30 is mounted in this member 29 and forms an upper bearing for the shaft 27, which extends through the rail 12 and is 65 reduced as at 31 to receive a hub 32 of the tenter chain sprocket gear 33 which is detachably secured to this hub by means of suitable bolts 34. The chain engaging part of the sprocket is formed of silent or non-metallic material. The hub 32 70 is keyed to the stub shaft 27 to rotate therewith and forms the driving means for one of the tenter chains, one link 36 of which is shown in engagement with the tooth 35 of this gear and in a 75 position to have its swinging jaw 36a opened by reason of its arm 37 engaging the opening flange

38 supported on the rotating hub of the sprocket gear.

By this arrangement the housings for the gears are supported by the bridge rails 13 and the end of the chain rail is supported on these bridge 5 rails rather than having this entire mechanism supported by and hanging from the extending end of the chain rail which is supported a substantial distance inwardly from the end of the rail, thus leaving this heavy portion partially 10 resting upon the drive shaft which extends through the casing. In order, however, to assist in supporting the rail I have provided a strut 39 which is bolted to the rail 12 as at 40 and 41, and which slidably engages the upper surface 42 15 of one of the rails to assist in supporting the rail directly from this bridge rail as well as being supported through the casing 14 and collar member 29 as above described.

In order that the rails may be moved toward 20 and from each other, I have provided screw shafts 43 on either side of the drive shaft 19 and in the same horizontal plane thereof and have housed one within each of the channeled bridge rails 13. These screw shafts are oppositely threaded from 25 their center outwardly toward their ends and extend through nuts 44 secured to the casing 14 through the projections 44a held in position in any suitable manner. These screw shafts are manipulated in unison by being connected together 30 through shaft 45 having worms 46 fixed thereon and engaging with the worm gears 47 on the end of the shaft 43. This shaft 45 is rotated from any suitable source of power through gear 48 upon one end of the shaft or may be manipulated 35 by hand, if so desired.

The chain rail itself has its head end portion formed in several sections. Two sections 50 and 51 (the former being shown in Fig. 6 as shaded for contrast), continue on the straight line path 40 of the general extent of the chain rail and these sections are each provided with channels 52 in which the tenter chain is guided and slides. An end section 53 is generally semi-circular and is provided with a channel 54 to connect the channels 52 and complete the track for the tenter chain. A flange 55 is provided on each of the sections 50 and 51 and this flange is tapered from its end 56 toward its end 56a so as to provide a narrower width and greater space for the chain 50 link as it tilts at an angle in its passage about the curved portion of its track. A flange 51, of the narrowed width, is on the end section 53 and thus this flange is continued about the periphery of the rail at the end thereof, thus preventing 55 the grease or lubricant from the chain from being discharged over the end of the rail as has been usual in machines of this character.

Downwardly extending lugs 58 and 59 respectively on the section 53 and on the sections 50 60 and 51 are secured together by suitable bolts 60 and nuts 61. By these separable sections the surfaces of the rail and flange may be machined and the parts assembled as above set forth. Further, the separable sections and the particular construction here provided enables the stub shaft 27 to be removed from the machine as well as the sprocket gear without dropping the casing and removing the drive shaft as was heretofore necessary in machines as customarily assembled and 65 placed on the market. Thus where repairs are necessary or replacement of worn parts, the labor involved for the change of these parts is materially reduced.

The foregoing description is directed solely to- 75

wards the construction illustrated, but I desire it to be understood that I reserve the privilege of resorting to all the mechanical changes to which the device is susceptible, the invention being defined and limited only by the terms of the appended claims.

I claim:—

1. In a tentering machine, a pair of chain rails, driving gearing at one end of the rails, support standards at spaced intervals for said chain rails, and bridge rails supported at the head end of the machine between and below the upper bearing surfaces of which the driving gearing is supported.
2. In a tentering machine, a pair of bridge rails at the head end of the machine, spaced chain rail supports, a pair of chain rails slidable along the supports, and a box containing driving gearing for the chain rails supported between and slidable along said pair of bridge rails.
3. In a tentering machine, a pair of bridge rails, a pair of chain rails, chains on said chain rails, driving gearing for the chain, said gearing being inclosed in a casing located below the upper bearing surfaces between and supported by the bridge rails at the head end of the machine.
4. In a tentering machine, a pair of generally channel shape bridge rails with their open faces toward each other, a gear mounting casing supported on and slidable along said rails and located between them, a chain rail secured to said casing and having a sprocket gear at the head end, means for slidably supporting said casing rails, and gears in said casing for driving said sprocket gear.
5. In a tentering machine, a pair of generally channel shape bridge rails, gear mounting casings supported on and slidable along said rails, chain rails secured to said casings and having a sprocket gear at the head end, means for slidably supporting said casings and chain rails, gears in said casing for driving said sprocket gear, and a threaded shaft housed in one of said bridge rails and having threaded engagement with said casings for relatively moving the casing and in turn the chain rails.
6. In a tentering machine, a bridge rail, gear mounting casings supported on and slidable along said rails, chain rail, means for supporting said chain rails on said casings, and a pair of threaded shafts disposed on opposite sides of said casing and having threaded engagement therewith for relatively moving the casings and in turn the chain rails.
7. In a tentering machine, a pair of generally channel shape bridge rails, gear mounting casings supported on and slidable along said rails, chain rails secured to said casings and each having a sprocket gear at the head end, means for slidably supporting said casing, gears in said casings for driving said sprocket gears, and a pair of threaded shafts housed within the bridge rails and disposed on opposite sides of said casings and having threaded engagement therewith for relatively moving the rails.
8. In a tentering machine, a pair of chain rails, driving gearing, a pair of bridge rails for supporting said driving gearing, and brace means secured to each of said chain rails and

slidable on and supported by one of said bridge rails.

9. In a tentering machine, a chain rail comprising two sections, a sprocket wheel on one section, drive gearing for said sprocket wheel, bearing supports for said sprocket and gearing secured to said last mentioned section, and means for removably securing said sections together.

10. In a tentering machine, a chain rail comprising a plurality of sections, a sprocket wheel on one section, gearing for operating said sprocket wheel, a housing for said gearing secured to said last mentioned section, and means for removably securing said sections together where- 15 by said sprocket, gearing, housing and section may be removed as a unit.

11. In a tentering machine, a pair of spaced bridge rails, gear mounting casings supported on and slidable along said rails, chain rails, means 20 for supporting said chain rails on said casings, and a threaded shaft located in a vertical plane passing between the distal portions of said bridge rails and having threaded engagement with the casings for moving the casings and in turn the 25 chain rails.

12. In a tentering machine, a pair of chain rails, a pair of screws for adjusting the distance of said rails one from the other, and a drive shaft maintaining slidable operative connection 30 with the chains on said rails and located in line with said adjusting screws.

13. In a tentering machine, a pair of chain rails, a pair of screws for adjusting the distance of said rails one from the other, and a drive 35 shaft maintaining slidable operative connection with the chains on said rails and located between and in line with said adjusting screws.

14. In a tentering machine, a pair of bridge rails of channel shape construction, a pair of 40 chain rails slidably supported on said bridge rails, a pair of screws located in said bridge rails for adjusting the distance of said chain rails one from the other, and a drive shaft maintaining slidable operative connection with the chains 45 on said rails and located in line with said adjusting screws.

15. In a tentering machine, a pair of bridge rails of channel shape construction opening inwardly, a pair of chain rails slidably supported 50 on said bridge rails, a pair of screws located in said bridge rails for adjusting the distance of said chain rails one from the other, and a drive shaft maintaining slidable operative connection with the chains on said rails and located be 55 tween and in line with said adjusting screws.

16. In a tentering machine, a pair of chain rails, spaced bridge rails providing supports for the chain rails at the head end of the machine, a drive shaft located in a vertical plane between 60 said bridge rails, and driving means for each chain rail driven from said drive shaft.

17. In a tentering machine, a pair of chain rails, spaced bridge rails providing supports for the chain rails at the head end of the machine, a drive shaft located in a vertical plane midway between said bridge rails, and driving means for each chain rail driven from said drive shaft.

RICHARD E. RUSDEN.
